UNITED STATES PATENT OFFICE.

DENNIS C. O'SHEA, OF CHICAGO, ILLINOIS.

GARMENT.

1,200,969.

Specification of Letters Patent.

Patented Oct. 10, 1916.

Application filed August 13, 1915. Serial No. 45,826.

To all whom it may concern:

Be it known that I, DENNIS C. O'SHEA, a citizen of the United States, residing at Chicago, in the county of Cook and State 5 of Illinois, have invented a new and useful Improvement in Garments, of which the following is a specification.

My invention relates to certain new and useful improvements in garments and my 10 object is, in general, to provide in combination with a garment of the character of a shirt, a girdle or waist portion carrying a part so arranged as to pass under the crotch of the wearer, thereby forming a 15 jock strap or supporter, which will perfectly perform its functions as such, and at the same time exert a slight downward pull on the garment from the shoulders thereof and cause it to fit snugly to the body of the 20 wearer.

It is a further object of my invention to provide an improved construction of those portions of a garment which form the jock strap or supporter.

25 Other objects and advantages of my invention will more fully appear from the following detail description of a specific embodiment thereof. In this description, reference will be had to the accompanying 30 drawings, in which,—

Figure 1 is a front elevation of an athletic or swimming shirt constructed in accordance with my invention, the tongue or flap being shown as hanging downward in 35 the inoperative position. Fig. 2 is a front elevation of a girdle constructed in accordance with my invention, this girdle being in substance nothing more or less than the lower portion of the shirt shown in Fig. 1, 40 but the flap, or tongue, being shown in the raised or operative position. Fig. 3 is an enlarged section taken on the line 3 of Fig. 2.

45 Referring more particularly to the drawing, the numeral 10 designates the body of my shirt, which in the illustration is shown as of the sleeveless type commonly used for swimming or athletic shirts. This shirt will preferably be constructed of knitted or 50 other elastic fabric in order to adapt itself most readily to the curves of the body.

The numeral 11 indicates the waist portion or girdle of the shirt which, as shown, is cut short at the side to terminate at or 55 slightly below the level of the hip of the wearer. The front section of the girdle

portion 11 is extended downward to form a tongue or flap 12 of such a length as to reach or perhaps extend a little beyond the crotch of the wearer. The rear portion of 60 the girdle is extended to form a tongue or flap 13 which, at its upper end, is of the shape of the flap 12 but which extends considerably below the same and has its lower portion enlarged, as at 14. The front flap 65 or tongue 12 is provided with a plurality of buttons, as shown, and the enlarged portion 14 of the rear flap 13 is provided with corresponding button-holes.

In Fig. 2 of the drawings, the upper or 70 body portion 10 of the shirt has been omitted, the garment being shown as a simple girdle 11', on which the flaps 12 and 13 are formed in precisely the same manner as was described in connection with the entire 75 shirt shown in Fig. 1.

In the use of my device the shirt body 10 or the girdle 11' will be put on in the customary manner, the flaps 12 and 13 being at that time disconnected as shown in Fig. 1. 80 When the garment is in place on the body, the flap 13 will be passed between the legs of the wearer and brought upwardly in front to lie over the flap 12. In the normal use of the device, the end button-holes 15 will then 85 be engaged over the end buttons 16, while the central button-hole 17 which, as shown, is in alinement with the button-holes 15, will be engaged over a button 18 out of alinement with and considerably below 90 the buttons 16. By this method of securing the flap 13 to the flap 12, a highly efficient jock-strap or athlete's supporter is formed. The requisites of such a 95 supporter are, in general, that it should maintain the male private organs in an inverted position and above the pubis bone, so that they are completely removed from the crotch and are held firmly but without great pressure against the soft wall of the abdomen. To accomplish this result the 100 supporter should fit firmly against the crotch and should have tightly stretched lateral edges bearing against the front of the abdomen in order to prevent the escape of the 105 parts laterally, and should provide a pocket or medial fullness or pouch in the center and between the tightly stretched lateral margins. These objects are fully attained by the manner of constructing and securing the 110 tongues 12, 13, in my garment. It will be noted that the end button-holes 15 being se-

cured over the upper buttons 16 serve to tightly stretch the lateral edges 19 of the tongue 13, thereby efficiently preventing the accidental displacement of the organs during violent exercise, while the central button-hole 17 being engaged over the lower button 18 permits the yielding fabric of which the garment is formed to bell outwardly to form a medial fullness or pocket 20, whereby the 10 parts are relieved from any undue pressure which might cause serious inconvenience, but are nevertheless held with sufficient firmness to prevent them from dropping downwardly into the crotch. The advantages of my invention are best obtained when the garment is constructed of knitted fabric, as described, for the reason that the pocket or pouch 20 will then form itself without the slightest wrinkling and by reason of the 15 manner in which the tongues are secured together. The exact form of this pouch or pocket is best shown in the cross-sectional view, Fig. 3.

In order to fit the garment for a greater 20 range of adjustability than is provided by the yielding qualities of the fabric itself, I may provide a second series of securing buttons, designated 16' and 18' respectively, suitably secured in a position lower down on the 25 tongue 12 than are the buttons 16 and 18. It is obvious that by securing the lower flap 13 to this lower series of buttons, the effective length of the garment, as of the shirt 30 10, is increased.

To still further increase the range of usefulness of my garment, I may provide a button 20' in alignment with the top button 16. If the garment is then worn by one who does not desire to take advantage of the pocket 35 40 or pouch 20, the central button-hole 17 may be secured over the button 20', in which case the tongues 12, 13, will lie smooth and tight against the abdomen. By suitably spacing the rows of buttons on the tongue 12, the 45 lower button 18 may be placed in alignment with the end buttons 16' so that when the flap 13 is secured to these latter buttons, the central button-hole 17 thereof may be engaged over the button 18 to obtain the same effect as is obtained when the buttons 16 and 50 55 20 are in use.

While my invention is particularly useful and possesses certain peculiar advantages when embodied in a bathing or athletic shirt of substantially the type shown in Fig. 1, it is nevertheless in its broader aspects capable of application to any body garment of the nature of a shirt or to a simple girdle, loin-cloth, or supporter, such as is illustrated by Fig. 2.

While I have described in considerable detail one specific embodiment of my invention in the foregoing description, it is to be understood that such description is not to be regarded as limiting my invention, but is 60 65 to be regarded as illustrative only and for the purpose of rendering my invention more clear, and I do not regard my invention as limited thereto, except in so far as such limitations have been included within the terms 70 of the following claim.

What I claim is:

A shirt having a narrowed lower front portion extending downwardly to form a flap or tongue and provided on its front face 75 with a plurality of buttons set at varying heights, and a rear tongue or flap portion of a length adapted to extend forwardly beneath the crotch of the wearer and upwardly on the front flap or tongue portion and provided adjacent its free end with a series of 80 button-holes adapted to engage at varying heights the buttons on the front flap or tongue portion, to produce a medial fullness or pouch portion and a lateral tension at its 85 edges for the purpose set forth.

DENNIS C. O'SHEA.

In presence of—

JOHN M. FELDHAKE,
WILLIAM C. KING.
